CLAIM

The ornamental design for a packaging box as shown and described.

DESCRIPTION

- 3. Packaging box
- 4. Packaging box
- 3.1 Front
- 3.2 Back
- 3.3 Left
- 3.4 Right
- 3.5 Top
- 3.6 Bottom
- 3.7 Unfolded
- 4.1 Front
- 4.2 Back
- 4.3 Left
- 4.4 Right
- 4.5 Top
- 4.6 Bottom
- 4.7 Unfolded

Designs 3-4 are used as packaging boxes for packaging laser toner cartridges. The front surface of each of the packaging

(Continued)

boxes forms the entire claimed design. The grayed-out sides of each of the packaging boxes form no part of the claimed design.
